UNITED STATES PATENT OFFICE.

CHARLES E. ANDERSON, OF LA PORTE, INDIANA.

FENCE-MACHINE.

SPECIFICATION forming part of Letters Patent No. 372,650, dated November 8, 1887.

Application filed July 12, 1887. Serial No. 244,092. (No model.)

To all whom it may concern:

Be it known that I, CHARLES E. ANDERSON, a citizen of the United States, residing at La Porte, in the county of La Porte and State of Indiana, have invented a new and useful Improvement in Fence-Machines, of which the following is a specification.

My invention relates to an improvement in machines for building fences; and it consists in the peculiar construction and combination of devices, which will be more fully set forth hereinafter, and particularly pointed out in the claims.

In the accompanying drawings, Figure 1 is a side elevation of a fence-machine embodying my improvements, showing the same in the act of building a fence. Fig. 2 is a rear elevation of the twisting device. Fig. 3 is a detached perspective view of the tension-equalizing device. Fig. 4 is a detail sectional view. Fig. 5 is a detached perspective view showing the manner of using one of the twisting-arms to tighten the wires in an old fence, and thereby take up the slack. Fig. 6 is a perspective view of a modification.

A represents a bar, which is provided with a series of arms, B, that project therefrom at right angles, the said arms being arranged at suitable regular distances apart and the bar being provided with any desired number of said arms. Each arm B has its inner end screw-threaded and extended through an opening in the bar A, and clamping-nuts C are screwed onto the threaded ends of the arms and bear against the front and rear sides of the bar A, thereby securely fastening the arms thereto. The outer ends of the arms B are curved downward, as at D, and are then bent outward at right angles, to form laterally-extending spindles E. At the inner end of these spindles is a washer, F.

G represents a series of twisting-arms, one of which is provided for each arm B. The said twisting-arms are curved in sigmoidal form, as shown, and are provided at their extremities with openings H, adapted to receive the spindles F, and thereby the said twisting-arms may be attached at either extremity to the spindles. In the central portions of the twisting-arms are made open slots I, which extend in opposite directions and are in line with each other, the said slots being only very

slightly larger than the diameters of the wires a, which are employed in making the fence. The twisting-arms are pivoted on the spindles 55 of arms B, as shown. Washers K are placed on the outer ends of the said spindles, and pins L are inserted in transverse openings in the said spindles to retain the washers and the twisting-arms in position thereon.

N represents a series of securing-cleats, which are secured to one side of the bar A, one of the said cleats being provided for each arm B. The said cleats have the oppositely-extending vertical arms O, and the spaces formed 65 between the said arms and the opposing side of the bar A are sufficient in width to receive the free ends of the twisting-arms. The outer side of the bar A is provided at a suitable distance from its upper end with a handle, P, 70 adapted to be grasped by the right hand of the operator.

R represents a tension device, which is adapted to be anchored at one end of the proposed line of fence. The construction of the 75 said tension device is as follows:

S represents a vertical frame comprising a pair of vertical boards, T, which are connected near their ends by means of cross-boards U, of suitable length.

V represents a pair of bolts, which connect the boards T near their upper and lower ends, and are provided with nuts whereby the said boards T may be clamped firmly on the ends of the boards U.

X represents a shaft, which extends transversely through the boards T, near the upper ends thereof. One end of the said shaft projects beyond one side of the frame, and to the opposite end of the frame is attached a crank, Y.

Z represents a pair of clamping-springs, which are preferably made of wood and connected together by means of a set-screw, A'. The upper ends of the said clamping-springs bear against opposite sides of the projecting 95 spindle of the shaft X, and the lower ends of the said springs are pivoted to one side of frame S by means of a bolt or pin, B'. By turning the set-screw the clamping-springs may be caused to bear against the spindle of the shaft 100 with any desired force, and thereby create as much friction as may be necessary to prevent retrograde rotation of the shaft.

C' represents a pair of vertical bars, which

are arranged parallel with each other and are connected at suitable regular distances by bolts D', on which are journaled rollers E', the said rollers being arranged between the bars C', as shown. From the center of the bars C' projects a rearward-extending pair of arms, F', the rear ends of which are connected by a transverse bolt, G', on which is journaled a pulley, H'.

10 I' represents a wire of suitable thickness, which is attached to the upper end of the frame S, is then passed around the pulley H', and has its opposite extremity attached to the shaft X and coiled thereon.

15 K' represents wires which pass over the rollers E' and have their free ends extending forward from the bars C'. To the said free ends of the said wires are attached clevises L', and between the arms of the said clevises are 20 journaled pulleys M'.

N' represents wires which pass around the rear sides of pulleys L, and have their front ends provided with eyes O'.

The operation of my invention is as follows:

25 A suitable post, b, is erected at one end of the proposed line of fence, and the tension device R is anchored in a vertical position at a suitable distance beyond the opposite end of the proposed line of fence by means of chains or 30 rods c, which are attached to the upper end of the tension device and to a stake, d, which is driven in the ground. The wires a are attached to the post b, are doubled thereon, and the ends of the wires are carried forward 35 and passed through the eyes in the wires N'. Loops are formed in the front ends of the wires a, and wooden blocks or pins e are inserted in the said loops and bear against the eyes of wires N', thereby firmly securing 40 the wires a thereto. The shaft X is then turned so as to cause the wire I' to be wound thereon, and thereby draw the equalizing device toward the tension device, and thereby stretch the wires a along the proposed line of 45 fence to the requisite tension. Inasmuch as the wires K' are permitted to slip freely over the rollers E', and inasmuch as the wires N' are permitted to slip freely over the pulleys M', the wires a will all be stretched at the same 50 tension, as will be readily understood. When the wires a have been stretched, the operator inserts the twisting-arms G between the pairs of wires and places each wire a in one of the slots I. The twisting device is in its initial position when the twisting-arms G are arranged vertically, as shown in Fig. 2. The operator slides the twisting device on the wires to within a slight distance of the post b, and he then grasps the handle P and moves the bar 55 A so as to cause the twisting-arms to describe circles, and thereby twist the wires a together, the twisting-arms being in a horizontal position when the wires are thus twisted, as indicated by dotted lines in Fig. 2. The picket f 60 is then inserted in the bights of the wires on the rear sides of the twisting-arms, the said picket is forced to within a suitable distance

of the post b, and the twisting device is then operated to cause the twisting-arms to rotate in the opposite direction from that previously 70 described, and thereby twist the wires on the front side of the picket. The twisting device is then moved forward a suitable distance on the wires, another picket is then inserted 75 in place and forced to within a suitable distance of the first picket, and the operation before described is then repeated, and so on until a sufficient number of pickets have been secured between the wires to form one panel 80 of the fence. The wires are then attached to a suitable fence-post by means of staples, and the before-described operation is continued until the fence is completed. As the wires are twisted together between the pickets, the tension of the wires is gradually increased until 85 they draw with sufficient strength to cause the shaft X of the tension device to uncoil the wire I' from time to time to a slight extent, and thereby prevent the wires a from breaking. When splices or knots in the wires are 90 encountered, the operator removes the wires from the slots of the twisting-arms, moves the twisting device forward a sufficient distance to clear the splices, and then reinserts the wires in the slots, as before. 95

I do not desire to limit myself to the use of the pulleys H' in the tension-equalizing device, as I may discard the said pulleys and employ semicircular yokes in lieu thereof, as shown in Fig. 4, the said yokes being provided 100 with peripheral grooves adapted to receive and retain the wires N'.

Fences constructed as hereinbefore described sag after a certain length of time, owing to the wires becoming stretched under the constant tensile strain to which they are subjected. In order to overcome this defect it is only necessary to detach one of the twisting-arms in my fence-machine and insert the pairs of wires a, successively, in one of the slots I 110 thereof, and rotate the said twisting-arm by hand, thereby making additional twists in the wires, and consequently taking up the slack therein.

If it is desired to merely cross the wires between the pickets when constructing the fence, this may be accomplished by operating the bar A so as to cause the twisting-arms to move through only half a circle. 115

In order to keep the wires parallel when 120 working over uneven ground, I provide a gage which is composed of a bar, P', having staples or keepers R' driven into it over each pair of wires, so as to confine the wires in place. This gage is moved along the wires in advance 125 of the twisting device from time to time, and keeps the wires disposed in parallel lines, as will be readily understood.

In Fig. 6 I illustrate a modified form of my twisting device, in which the bar A has the 130 arms B, and the twisting-arms are shortened and provided at only one extremity with an opening, through which they may be pivotally bolted to the arms B. In this modified form

the cleats have arms S', that project outward from the bar A, and have vertical heads T' attached to their outer ends and arranged at a suitable distance from the opposing sides of 5 the arms B, so that the free ends of the twisting arms are free to pass between the cleats and the arms B.

Having thus described my invention, I claim—

10 1. The combination, in a wire-twisting machine for building fences, of the bar A, the cleats N on one side thereof, having the vertical arms O extending in opposite directions, the arms B, projecting from one side of the bar A 15 at right angles to the cleats, and the twisting arms G, each having one end pivoted to the outer end of one of the arms B, the said twisting-arms being provided in opposite sides

with the open slots I, substantially as described.

2. The tension-equalizing device for the wires of a fence, the said device having the bars C', the rollers E', the wires K', passed around the said rollers, the pulleys attached to the free ends of the said wires, and the 25 wires N', passed around the said pulleys and adapted for the attachment of the fence-wires, substantially as described.

In testimony that I claim the foregoing as my own I have hereto affixed my signature in 30 presence of two witnesses.

CHARLES E. ANDERSON.
